UNITED STATES PATENT OFFICE

160,775

JEWELRY CHAIN

Erwin W. Deines, Cranston, R. I., assignor to
Chain Craft Co., a corporation of Rhode Island

Application May 24, 1950, Serial No. 10,140

Term of patent 7 years

(Cl. D45—16)

To all whom it may concern:

Be it known that I, Erwin W. Deines, a citizen of the United States of America, residing at Cranston, county of Providence, State of Rhode Island, have invented a new, original, and ornamental Design for a Jewelry Chain, of which the following is a specification, reference being had to the accompanying drawing, forming a part thereof.

Fig. 1 is a top plan view of a section of the jewelry chain, showing my new design;

Fig. 2 is an edge elevation;

Fig. 3 is a perspective view of one of the links; and

Fig. 4 is an end view of one of the links.

I claim:

The ornamental design for a jewelry chain, substantially as shown.

ERWIN W. DEINES.
